UNITED STATES PATENT OFFICE.

GEORGE E. KELLY AND ELIJAH J. EMERY, OF WILKES-BARRE, PENNSYLVANIA.

MECHANIC'S APRON.

1,139,532.

Specification of Letters Patent. Patented May 18, 1915.

Application filed March 10, 1914. Serial No. 823,803.

To all whom it may concern:

Be it known that we, GEORGE E. KELLY and ELIJAH J. EMERY, citizens of the United States, residing at Wilkes-Barre, in the county of Luzerne and State of Pennsylvania, have invented new and useful Improvements in Mechanics' Aprons, of which the following is a specification.

This invention relates to garments, and particularly to protecting garments to be worn by mechanics or the like for the protection of the ordinary clothing; and it has for its primary object the provision of a garment of this character which may be readily applied to the person to properly and effectually protect the trousers and which will include a bib or apron arranged at the front of the garment and adapted to afford a double protection to the ordinary garments of the wearer.

Another object of the invention is the provision of a garment of this character which may be quickly and conveniently applied to the person without the trousers of the person being soiled by having to extend the feet downwardly through the legs of the garment, the sides of the garment or legs thereof being divided longitudinally whereby the legs of the wearer may be placed into the legs of the garment sidewise and the legs of the garment then buttoned up along their divided portions and properly connected.

A further object of the invention is the provision of a garment of this character in which the different parts thereof may be thoroughly cleaned and laundered as the occasion may demand.

With these and other objects in view, the invention consists of certain novel features of construction, combination and arrangement of parts, as will be hereinafter described and claimed.

In the accompanying drawings:—Figure 1 is a perspective view of the garment, looking at the front thereof, and showing the same applied; Fig. 2 is a similar view, looking at the back of the garment; Fig. 3 is a plan view of the blanks from which the trousers portion of the garment is formed; Fig. 4 is a view similar to Fig. 1, showing a slightly modified form of the invention; Fig. 5 is a similar view, looking at the back of the garment.

Referring first to the garment as shown in Figs. 1—2—3, the same comprises trousers,

1 which may be made of any suitable number of pieces and the legs 2 of which are open at the outer sides. The front 3 of each leg is provided with buttons or similar fastenings 4 which are adapted to be fitted in button holes or similar receiving means 5 on the back portion 6 of the garment. The said back portion 6 is provided at its waist line with a buckle 7, in which a tape 8 is 65 adjustably connected. This tape has one end secured to an adjacent portion of the waistband of said back of the garment so that when the tape is drawn through the buckle the garment may be taken up around 70 the waist of the wearer.

In forming the trousers in the described manner it is evident that the necessity of having to place the legs in a downward direction through the legs of the garment in 75 fitting the latter to the person, will be eliminated as the sides of the legs of the garment may be separated and the legs of the person may be placed sidewise into the legs of the garment and the sides of the legs then 80 buttoned up through the provision of the means hereinbefore specified. In this manner, dirt contained on the shoes of the person will be held against smearing the inside surface of the legs of the garment and such 85 dirt will be positively held against marring the ordinary trousers of the wearer. By constructing the trousers in this manner it will also be seen that they may be thoroughly cleaned and laundered as the occasion may necessitate.

The back portion of the garment is provided along the hip-line with a suitable pocket 9. The front portion of the garment may be provided with a suitable fly 10 and 95 at the waist-line of the said front portion of the trousers of the garment may be provided with a suitable fly 10 and at the waist-line of the said front portion of the trousers of the garment may be stitched 100 or otherwise suitably secured a relatively long protecting apron 11, which is adapted to fully extend down over the front of the person and to thereby afford a double protection to the clothing of the wearer. 105 Above the waist-line the apron is extended to form a bib 12, which extends over an adjacent portion of the shirt or coat of the wearer, and as illustrated the sides of the bib are curved gradually along the line 13 110 into the adjacent vertical sides of the main body portion of the apron so that said ver-

- tical sides may be snugly folded around the adjacent sides of the person and then held in such position by tapes 14, 14 arranged at the upper corners of the apron and at the 5 juncture of the bib with the main body portion of the apron. These tapes may be extended around the waist of the wearer and then tied to properly hold the apron in position.
- 10 As a shoulder suspension for the garment, the bib portion of the apron is provided at one corner with a strap 15, which is adapted to be extended along the neck or over the shoulders of the wearer and to be connected 15 with a button 16 at the opposite corner of the bib through a form of fastening 17 having a buckle 18 which may be connected to any part of the length of the strap that may be necessary to cause the garment to properly fit upon the person. The bib of the 20 garment is provided with a pocket 19 and below the bib the main body portion of the garment is provided with a similar pocket 20.
- 25 In the form of the invention shown in Figs. 4 and 5 the trousers of the garment is similar to the trousers of the garment described in the preferred embodiment of the invention, the difference being in providing 30 one side of each slit leg with a longitudinal series of resilient heads or fastenings 21 that are adapted to be received in resilient sockets 22 on the other portion of the split leg. At the waist-line of the 35 trousers and at the front thereof is an apron 23 similar to the apron in the preferred embodiment of the invention. This apron is provided with a waist connection in the form of tapes 24, 24 that may be extended 40 around the waist of the wearer and then be tied together as in the form of the invention described in Figs. 1 to 3, inclusive. The apron is then extended above the trousers of the garment, so as to form a bib
24. The upper corners of the bib are provided with resilient heads 27, 27 that are adapted to be fitted in resilient sockets 28, 28 carried by shoulder straps 29, 29. These straps cross each other at the back of the garment and they are secured together at 30 50 and the lower rear ends of the straps are stitched or otherwise suitably secured to the back portion of the trousers of the garment along the waist line, as at 31. In this form of the invention the bib at the upper 55 portion of the apron has secured thereto a single length of material 32. Longitudinal lines of stitching 33 are taken in the bib and in said material so as to separate the latter into different communicating subdivisions. The material is thus arranged so as to define with the bib of the garment a pocket in which a rule, pencil or other similar objects or tools may be arranged and conveniently carried upon the garment. 60 The apron is provided below the waist-line with a suitable pocket 34. In other respects this form of the invention is identical with the form referred to in Figs. 1, 2 and 3.
- 65 We claim:—
- 70 A garment of the class described having trousers provided with legs each having a vertical divided portion and means for holding the divided portion of each leg in a closed condition, and said trousers having 75 securing and adjusting devices on their rear side, and an apron extending over and secured to the front of the trousers at a point along the waist line the apron being open on its rear side and being provided with securing and adjusting means.
- 75 In testimony whereof we affix our signatures in presence of two witnesses.
- GEORGE E. KELLY.
ELIJAH J. EMERY.
